(57) **CLAIM**

What is claimed is the ornamental design for a medical gown, as shown and described.

DESCRIPTION

FIG. 1 is a front elevation view showing the medical gown of Applicants' invention.

FIG. 2 is a rear elevation view of the medical gown of FIG. 1.

FIG. 3 is a front perspective view of the medical gown of FIG. 1.

FIG. 4 is a rear perspective view of the medical gown of FIG. 1.

FIG. 5 is an enlarged rear perspective view of the medical gown of FIG. 1 taken of "area 5" shown in FIG. 4.

FIG. 6 is an enlarged rear perspective view of the medical gown of FIG. 1 taken from a perspective of "arrow 6" shown in FIG. 4; and,

FIG. 7 is an enlarged rear perspective view of the medical gown of FIG. 1 taken from a perspective of "arrow 7" shown in FIG. 4.

The "dash-dash" broken lines show portions of a medical gown which form no part of the claimed design.

1 Claim, 6 Drawing Sheets
